ATTORNEY

UNITED STATES PATENT OFFICE

JOHN A. ANDRUSIS, OF BROOKLYN, NEW YORK

VEGETABLE SLICER

Application filed February 7, 1928, Serial No. 252,598. Renewed April 5, 1930.

This invention relates to a device for slicing vegetables and other articles, the general object of the invention being to provide a frusto-conical member rotatably supported 5 in a frame and having slots therein over which are placed the slicing knives, with means for adjusting the knives and the width of the openings to vary the size of the slices being cut from the article.

10 Another object of the invention is to provide a hopper which is so arranged as to hold the articles at an inclination so that they will properly engage the knife carrying member and to provide a presser member 15 for pressing the articles against the knife carrying member.

A still further object of the invention is to make the parts removable and collapsible so that the device will occupy but little space 20 when stored.

This invention also consists in certain other features of construction and in the combination and arrangement of the several parts, to be hereinafter fully described, illustrated in the accompanying drawings and 25 specifically pointed out in the appended claims.

In describing my invention in detail, reference will be had to the accompanying 30 drawings wherein like characters denote like or corresponding parts throughout the several views, and in which:—

Figure 1 is a front view of the device.

Figure 2 is a plan view.

35 Figure 3 is a section on line 3—3 of Figure 1.

Figure 4 is a section on line 4—4 of Figure 3.

40 Figure 5 is a rear view of the knife carrying member.

Figure 6 is a front view of a portion of the knife carrying member, showing a strip for reducing the width of the slot therein.

45 Figure 7 is a detail sectional view through a slotted portion of the knife carrying member and through one of the knives.

Figure 8 is a similar view, but showing a strip in place for regulating the width of the slot.

50 Figure 9 is a view of one of these strips.

Figure 10 is a section on line 10—10 of Figure 2.

In these drawings, A indicates a supporting frame which comprises the rectangular frame 1 having the cross piece 2 adjacent its rear end, and the yokes 3 which are pivotally secured to the frame 1 and form the legs of the supporting frame. By pivoting these yokes to the frame 1, they may be folded into alignment with the frame 1 so that the supporting frame will occupy but little space when knocked down. A shaft 4 is journaled in the rear part of the frame 1 and in the cross piece 2 and has a crank 5 connected with its outer end and a disk 6 connected to its inner end. This disk is formed with openings. The front member of the frame 1 is formed with a bearing notch 7.

A frusto-conical member 8 has its small 70 end closed and its other end open and a spider 9 is connected to the large end and carries a hub 10 which is formed with a pintle 11 to engage the bearing 7. A latch 12 holds the pintle in the bearing. The 75 small end of the member 8 is detachably connected with the disk by having headed studs 13 thereon engaging keyhole shaped openings (not shown) in the disk, latches 14 being pivoted to the disk to hold the studs 80 in the openings. Thus the member 8 is removably supported in the supporting frame so that it can be replaced by a different form of cutting member when desired. As the means for connecting member 8 with the 85 disk forms a part of my application filed February 7, 1928, Serial Number 252,599, it is not thought necessary to describe this connection in detail.

The member 8 is formed with the elongated slots 15 and a blade 16 is arranged to overlap each slot and each blade is detachably connected with the member 8 by means of the screws 17. Adjusting screws 18 are also provided for adjusting each blade, 95 these screws passing through threaded holes in the member 8 and engaging the ends of the blades so that by loosening the small screws 17 and tightening the adjusting screws 18, the blades can be adjusted away 100

from the member 8 so that they will make the slices cut from the article being operated upon of greater thickness than they would be if the blades were in contact with the member 8. Thus I have provided means for varying the thickness of the slices cut by the device.

I also provide means for regulating the width of the slots 15 to regulate the thickness of the slices being cut, such means comprising the strips 19, one of which is placed adjacent each slot and each strip is held in place by a screw 20 passing through the outer end of the strip into a threaded hole in the member 19 and by a set of tongues 21 arranged on the inner end of each strip and engaging the inner end wall of the slot, one tongue being offset from the other, as shown in Figure 9, so that the tongues can straddle the wall. Thus when these strips are in place, the slots are of less width than they are when the strips are not used. As shown, the strips are placed on the interior circumference of the member 8, with the blades 16 on the exterior circumference.

A substantially semi-circular cover member 22 is detachably connected with the frame 1 by means of pins carried by one end of the cover member engaging holes in the frame 1 and a latch 23 at the other end of the cover member engaging suitable keeper means at the other end of the frame 1 so that by moving the latch to releasing position, the cover member can be lifted from the frame. The latch end of the cover member is provided with a handle 24 for facilitating the handling of the cover member and this handle can also be used to steady the device when it is in operation. The rear of this cover member is closed and its front is open. This front is provided with a reduced extension 25 which is connected with the major portion of a wall 26. A pair of spaced partitions 27 is placed in the cover member and these partitions and a part of the rear wall thereof form a hopper, the lower edges of the partitions being so shaped that the bottom of the hopper is closely aligned with the exterior circumference of the member 8 so that articles placed in the hopper will be engaged by the slicing knives carried by the member 8. The slices cut from this material will pass through the slots 15 and drop upon the interior walls of the member 8 and slide down the same and thus pass from the member into a dish or other receptacle placed under the device to receive the same.

A trough-shaped hopper 28 is detachably held in the first hopper by means of the pins 29 on its lower end engaging holes formed in the walls of the first hopper and the parts are so arranged that the hopper 28 will extend upwardly and rearwardly at an angle, as shown in Figures 1, 2 and 3 of the drawings. The lower end of the hopper 28 is

shaped so that articles placed therein will be engaged by the knives on the member 8. A presser member 30 of considerable weight is slidably arranged in the hopper 28 by having the projections 31 thereon engaging an elongated slot 32 formed in the bottom of the hopper 28, the major portion of the slot being covered by a covering member 33 fastened to the exterior part of the hopper. Pointed projections 34 are carried by the lower end of the member 30 for engaging the articles placed in the hopper to hold the articles firmly therein and against the knives and the lower end of the slot 32 is so spaced from the lower end of the hopper that downward movement of the member 30 is limited so as to prevent the projections 34 being struck by the knives. A handle 35 is fastened to the member 30 so that said member 30 can be easily adjusted in the hopper and a hook 36 is carried by the upper end of the member 30 and is adapted to engage the upper end of the hopper to hold the member 30 in raised position. The slot is placed in a longitudinally extending depression 37 in the bottom of the hopper and the member 30 is formed with a thickened portion for engaging this depression, as clearly shown in Figure 4.

A front apron 38 and side aprons 39 are provided for preventing material from the cutting means being thrown to the sides or front of the device, these aprons directing the material into the dish. The side aprons 39 are pivoted to the frame 1 so that they can be folded into the frame when the supporting frame is collapsed.

From the foregoing it will be seen that vegetables or the like, placed in the hopper 28, will be pressed by the member 30 against the member 8 so that when said member 8 is rotated by the handle, the knives 16 on said member 8 will cut slices from the article in the hopper, these slices dropping into the member 8 and falling from the front end thereof into the dish or receptacle placed under the device. As before stated, the thickness of the slices can be varied by adjusting the knives and also by using the strips 19. It will, of course, be understood that when desired, the hopper 28 can be removed and the hopper formed by the partitions 27 can be used alone, but this hopper 28 is desirable to use with vegetables of considerable length, such as carrots, beets and the like. The handle 35 is used to raise the member 30 so that the hook can be placed over the upper end of the hopper, while articles are being placed in the hopper and said handle can also be used to apply additional pressure to the articles. The supporting frame can be knocked down and the cover, the hopper and the knife carrying member removed so that the device will occupy but little space

when not in use. This also enables the parts to be easily cleaned and by making the member 8 removable, a similar member, such as a grater or a member provided with different forms of knives can be substituted therefor.

It is thought from the foregoing description that the advantages and novel features of my invention will be readily apparent.

10 It is to be understood that I may make changes in the construction and in the combination and arrangement of the several parts, provided that such changes fall within the scope of the appended claims.

15 What I claim is:—

1. A device of the class described comprising a frame, a cover thereon, a hopper carried by the cover, a frusto-conical member rotatably mounted in the frame, a handle for turning the member, said member having slots therein, a knife located adjacent each slot, means for adjusting the knives towards and away from the member to vary the thickness of the slices cut from the articles operated upon, and strips adjustably connected with the member for regulating the width of the slots.

2. A device of the class described comprising a frame, a cover thereon, a hopper carried by the cover, a frusto-conical member rotatably mounted in the frame, a handle for turning the member, said member having slots therein, a knife located adjacent each slot, means for adjusting the knives to vary the thickness of the slices cut from the articles operated upon, and means for regulating the width of the slots, such means comprising a strip for each slot, means for detachably connecting one end of the strip to the member and tongues on the other end of the strip for straddling an end wall of the slot.

3. In combination with a vegetable cutter having an upright hopper having holes in its walls, a diagonally arranged trough shaped hopper having its lower end entering the first hopper and pins on said lower end engaging the holes.

45 In testimony whereof I affix my signature.
JOHN A. ANDRÜSIS.
